(57) **CLAIM**

We claim the ornamental design for a visor, as shown and described.

DESCRIPTION

FIG. 1 is a top plan view of a visor.

FIG. 2 is a bottom plan view of the claimed design.

FIG. 3 is a front elevation view of the claimed design.

FIG. 4 is a rear elevation view of the claimed design.

FIG. 5 is a side elevation view of the claimed design; and, FIG. 6 is a perspective elevation view of the claimed design. The sunglasses depicted in broken lines in FIG. 5 is environmental matter that forms no part of the claimed design. In FIGS. 1-2, 5 and 6 a stitching line is shown on the visor that forms part of the claimed design.
